United States Patent Office

Des. 233,388
Patented Oct. 29, 1974

233,388

DISPLAY STAND OR SIMILAR ARTICLE

Jerome A. Moss, 107 E. 31st St.,
New York, N.Y. 10016

Filed Mar. 12, 1973, Ser. No. 340,445

Term of patent 14 years

Int. Cl. D6—04

U.S. Cl. D6—153

FIG. 1 is a front, top and left side perspective view of a display stand or similar article showing my new design; FIG. 2 is a right side elevational view; and FIG. 3 is a rear elevational view.

I claim:

The ornamental design for a display stand or similar article, substantially as shown.
